UNITED STATES PATENT OFFICE.

JOHN H. KNIGHT, OF WINSTON SALEM, NORTH CAROLINA.

MAIL-BAG CATCHER AND DELIVERER.

No. 909,611.

Specification of Letters Patent.

Patented Jan. 12, 1909.

Application filed September 19, 1908. Serial No. 453,763.

To all whom it may concern:

Be it known that I, JOHN H. KNIGHT, a citizen of the United States, residing at Winston Salem, in the county of Forsyth and

5 State of North Carolina, have invented new and useful Improvements in Mail-Bag Catchers and Deliverers, of which the following is a specification.

This invention relates to mail bag catchers 10 and deliverers, the object of the invention being to provide a simple and reliable apparatus of novel construction for delivering a mail bag at a station and at the same time catching or picking up another bag, the apparatus being of such nature as to insure the proper delivery and picking up of bags without injuring or mutilating the same.

With the above general object in view, the invention consists in the novel construction, 20 combination and arrangement of parts as hereinafter fully described, illustrated and claimed.

In the accompanying drawings, Figure 1 is a perspective view showing the catching 25 and delivering apparatus complete and the relation of the same to a car. Fig. 2 is a plan view thereof. Fig. 3 is a vertical cross-section through the same, showing the parts of the apparatus in their operative relation. Fig. 4 is a simliar view showing the catcher 30 and deliverer swung back into the car door opening. Fig. 5 is a longitudinal vertical section illustrating the operation of the apparatus.

35 At each station there is arranged a platform or stand embodying suitable supporting legs 1, cross sills 2 supported thereby and slats or rails 3 secured upon the cross sills 2 and arranged at suitable distance 40 apart and parallel to each other to leave parallel ways or channels 4, the purpose of which will hereinafter appear. The opposite ends of the slats or rails 3 may be beveled or pointed as indicated at 5 to form flaring 45 entrance throats to the ways or channels 4. The stand or platform also comprises a trip 6 which is shown in the form of a laterally projecting stud the outer end of which is supported by means of a brace or bracket 7 50 secured to the platform.

The catcher and deliverer consists of a frame embodying oppositely arranged side pieces 8 connected by a cross-bar 9 which forms a bag stop and also connected by a 55 cross piece 10 which also acts as a bag stop and which extends inward beyond the inner

side piece 8 and has its end pivotally mounted at 11 in a base 12 securely fastened to the floor of the car as indicated in the drawings. The object in so pivoting the 60 frame of the deliverer as a whole is to enable the same to be set either in a substantially horizontal position to project outward from the plane of the car side as shown in Figs. 1, 2 and 3, or to be folded upward and inward 65 within the car door opening as shown in Fig. 4. In order to hold the frame in either position referred to, a latch lever 13 is mounted on the bar 10 and the point of said lever is adapted to engage with a shoulder 14 on the 70 base 12 for holding the catcher folded as shown in Fig. 4, or with another shoulder 15 on the base for retaining the catcher securely in its operative position as shown in Fig. 3, the latch 13 being thrown into engagement 75 with either one of said shoulders by means of a spring 16.

Projecting in the opposite directions from the main supporting bar 10 is a plurality of bag engaging fingers 17 having their upper 80 sides concaved as shown at 18 and their ends pointed as at 19. These fingers extend parallel to the length of the car and parallel to each other and are spaced apart at the proper distances to cause them to traverse the ways 85 or channels 4 between the slats or rails 3, as the car passes a station, the fingers 17 traveling beneath the plane of the top edges of the slats 3 as shown in Fig. 5.

Mounted on the catcher and deliverer is a 90 curved guard 20 adapted to partially close in one end of the catcher frame, the said guard being provided at opposite sides with arms 21 which are pivotally mounted at 22 on the side pieces 8. One of the arms 21 is 95 provided with a fork 23 having the opposite blades or prongs thereof beveled on their inner sides and pointed as shown at 24 to provide a wide flaring entrance throat into which the trip stud 6 above described passes 100 as the catcher travels over the platform.

In the use of the apparatus, a mail bag is placed by the operator on the car in the rear compartment of the catcher, and this may be done while the catcher is in its folding position shown in Fig. 4, the catcher being then swung outward to its horizontal or operative position and held by the latch 13, the guard 20 partially covering said rear compartment and preventing the mail bag from escaping 105 therefrom before reaching the station. The mail bag to be received is placed across the

slats 3 as shown in Fig. 3. When the fork 24 strikes the trip 6, the guard 20 is reversed or swung over the top of the catcher to the opposite side, and this occurs just after the bag on the platform has been caught by the adjacent fingers 17. As the catcher moves on, the bag is thus dragged off the platform by the advance fingers and the other bag is released by the rear fingers and left upon the platform.

Having thus fully described the invention, what is claimed as new is:—

1. Mail bag catching and delivering apparatus embodying a stationary platform, and a car supported element comprising pick up and delivery fingers, and a reversible guard.
2. Mail bag catching and delivering apparatus embodying a stationary platform, and a car supported element comprising pick up and delivery fingers, a shiftable guard, and means for shifting the guard as the car supported element passes the platform.
3. Mail bag catching and delivering apparatus embodying a stationary platform, a trip thereon, and a car supported element comprising pick up and delivery fingers, a pivoted guard mounted thereon, and a guard shifting fork adapted to be acted upon by the trip on the platform, substantially as and for the purpose described.
4. Mail bag catching and delivering apparatus embodying a stationary platform, provided with a trip, and a car supported ele-

ment embodying fore and aft compartments, a guard shiftable from one compartment to the other and means connected with said guard and adapted to coöperate with the trip on the platform for moving the guard from one compartment to the other.

5. Mail bag catching and delivering apparatus embodying a stationary platform, and a car supported element comprising pick up and delivery fingers, a shiftable guard, means for shifting said guard as it passes around the platform, and means for folding the car supported element out of the way, substantially as described.

6. Mail bag catching and delivering apparatus embodying a stationary platform, and a car supported element comprising pick up and delivery fingers, a guard shiftable from one set of fingers to the other, and means for automatically shifting said guard as it passes along the platform, means whereby the said element is pivotally mounted on the car so as to project outward therefrom and to be swung inward through the door opening, and means for rocking said element in its operative position.

In testimony whereof I affix my signature in presence of two witnesses.

JOHN H. KNIGHT.
